UNITED STATES PATENT OFFICE.

ADOLPH DIETSCHE, JR., OF NEW YORK, N. Y., ASSIGNOR TO AMERICAN LITHOGRAPHIC COMPANY, OF NEW YORK, N. Y., A CORPORATION OF NEW YORK.

DISPLAY DEVICE.

Application filed February 8, 1922. Serial No. 534,851.

To all whom it may concern:

Be it known that I, ADOLPH DIETSCHE, Junior, a citizen of the United States, and a resident of New York, borough of Queens, 5 in the county of Queens and State of New York, have invented certain new and useful Improvements in Display Devices, of which the following is a specification.

This invention relates to display devices, 10 and particularly to that class thereof intended for window or counter use and which may represent colorful lithographic facsimiles of real merchandise. The object of my improvements is to provide a device of 15 the class specified of simple construction, which can be laid flat for shipment and which can be erected into display condition with little effort.

The preferred embodiment of the invention is illustrated in the drawing accompanying this specification, in which:—

Figure 1 is a perspective view of the display device erected for use.

Fig. 2 is a top plan view of the blank 25 as cut from the sheet.

Fig. 3 is an enlarged partial top plan view showing the securing elements interlocked, back of the box cover.

Figs. 1 and 3 are to one scale, and Fig. 30 2 is to a scale about half that of the other figures.

In the drawing, numeral 5 designates a fictitious container displaying merchandise such as cigars, or the like, cover 6 appearing to be raised for exhibiting the contents of the container, which is apparently supported on a display stand having a front base member 7 provided with feet 8 and 9 and rearwardly extending base slides 10 and 11, respectively, each being provided with feet 12 and 13, the latter or rear feet being shorter than the forward feet, causing the device to be inclined backwardly.

The blank, as illustrated in Fig. 2, is represented as a flat lithographed form cut integrally from sheet material, and consists essentially of a front wall including the elements 5 to 9 inclusive, and the two

side members which include the base elements 10, 11, the fictitious container ends 14, 15, and flaps 16, 17, respectively.

Lines of demarcation for bending or scoring are shown by vertical dotted lines 18, 19, at the point of articulation between the front wall and the side walls, respectively, and in like manner horizontal dotted lines 20, 21, indicate the points at which the extending side flaps 16, 17 are bent to form the box corners, as 22, respectively.

Separation of the ends, respectively, of the upper portion 6 of the front wall from the side flaps 16, 17, is provided by narrow slots 23, 24, extending vertically downward from the top edge of element 6 to the horizontal bending lines 20, 21.

Near the upper ends of side flaps 16, 17, are provided means for securely holding them together when bent in horizontal position.

Said means preferably include a vertical slot 25, transversely central of side flap 17, and an associated locking tongue 26 on side flap 16, formed by a curved slot 27 extending inwardly from the vertical slot 23 to 75 a point midway of side flap 16, and an arcuately curved notch 28 at the upper end 29 of flap 16, providing a tongue of uniform width throughout its length.

In securing the interlocking elements together, side flap 16 is disposed over side flap 17, and tongue 26, on being slightly depressed, is entered into slot 25, firmly interlocking the top elements of the structure, which is obviously open at the back and bottom, but presents the appearance, from the front, of a box resting upon a support and having its cover raised to display its contents.

I claim:

1. In a display device the combination of a front wall, opposite end walls articulated thereto, and a flap articulated to the upper edge of each end wall, said flaps having means for mutually interlocking and said end walls terminating downwardly in feet adapted for supporting the display, the front and end walls being held in angular

relation and the device in display position by the interlocking of said flaps.

2. In a display device the combination of a front wall, opposite end walls articulated thereto, and a flap articulated to the upper edge of each end wall, said flaps having means for mutually interlocking, said front wall projecting above said flaps when interlocked, said front and end walls terminating

downwardly in feet at their lateral outer 10 portions, the adjacent front and end wall feet being articulated together, the front and end walls being held in angular relation and the device in display position by the interlocking of said flaps.

In witness whereof, I hereby affix my signature this 3d day of February, 1922.

ADOLPH DIETSCHE, JR.
